ADJUSTABLE HEADWEAR SWEAT BAND FEEDER

Anne Stangler, New York, N. Y.

Application October 23, 1952, Serial No. 316,464

5 Claims. (Cl. 112—152)

This invention relates to an adjustable headwear sweat- 15
band feeder.

It is an object of the present invention to provide an 20
adjustable headwear sweat-band feeder which may be
readily and easily attached to a conventional sewing
machine and which may be readily and easily adjusted to
accommodate sweat-bands of different widths while the
head-band is being stitched in position on a headwear.

It is another object of the present invention to provide 25
an adjustable headwear sweat-band feeder comprising a
presser-foot formed at one end with a slot for attach-
ment to a conventional sewing machine and provided at
the other end with a channel, the width of which channel
may be adjusted by a head-strap formed with a slot for 30
selectively securing the head-strap by means of a screw
to guide sweat-bands of different widths through the
device while the head-band is being stitched in position on
a headwear by the needle of the sewing machine.

It is another object of the present invention to provide 35
an adjustable headwear sweat-band feeder of the above
type wherein a head-strap is formed with a downwardly
projecting extension adapted to engage the front edge of
the device to prevent angular movement of the head-strap
around a securing screw.

It is still another object of the present invention to pro- 40
vide an adjustable headwear sweat-band feeder adapted
to cooperate with a spool assembly rotatively supported
on a stand above the sewing machine for guiding the
sweat-band used for headwear into the adjustable head-
wear sweat-band feeder.

It is still another object of the present invention to pro- 45
vide an adjustable headwear sweat-band feeder which may
be used for a right or left-hand feeder.

For further comprehension of the invention, and of 50
the objects and advantages thereof, reference will be had
to the following description and accompanying drawings,
and to the appended claims in which the various novel
features of the invention are more particularly set forth.

In the accompanying drawings forming a material part 55
of this disclosure:

Fig. 1 is a fragmentary front elevational view of a sewing 55
machine to which the invention, shown partly in section,
is applied.

Fig. 2 is a view thereof in end elevation.

Fig. 3 is a perspective view of the invention adapted 60
for right-hand feed.

Fig. 4 is a perspective view of one of the parts shown 65
in Fig. 3.

Fig. 5 is a perspective view of the invention adapted 70
for left-hand feed.

Fig. 6 is a perspective view of one of the parts shown 75
in Fig. 5.

Fig. 7 is a vertical sectional view taken along line 7—7 80
of Fig. 3.

Fig. 8 is an end elevational view taken along line 8—8 85
of Fig. 5.

Fig. 9 is a front elevational view of the spool assembly 90
rotatively supported for guiding the sweat-band used for
headwear into the adjustable feeder.

Fig. 10 is a fragmentary end elevational view thereof. 95

Fig. 11 is a fragmentary perspective view of a part of 100
the spool assembly shown in Figs. 9 and 10.

Fig. 12 is a fragmentary perspective view of another 105
part of the spool assembly shown in Figs. 9 and 10.

Referring now in detail to the figures, the invention is 110
shown in operative use on a well-known type sewing ma-
chine of the type shown in Patent No. 1,085,401 having

an arm or standard 10, a main shaft 11, an oscillating 15
arm 12 operated from an eccentric on the main shaft 11,
a reciprocating needle bar 13, a presser-foot shaft 14,
and a bottom feed-dog 15 receiving the usual compound
oscillatory movement derived from eccentrics on the main
shaft 11 through suitable intermediate levers. All of the
aforementioned parts are constructed and operated in
the usual manner and it will be understood by those
skilled in the art that any other usual or suitable con-
struction and operation may be employed so far as the
application of the present invention is concerned.

Referring now particularly to Figs. 1, 2, 5, 6 and 8, 20
there is shown a modified presser foot consisting of the
usual hook-shaped bracket 16 having a slot 17 for at-
tachment to the bottom of the presser-foot shaft 14 by
means of a screw 18, but being integrally formed at the
end thereof remote from the slot 17 with an upwardly
bent, base member 19. The presser-foot 16 adjacent the
member 19 is provided with a slot 20 receiving needle 21.

The base member 19 consists of a rectangular bar ex- 25
tending from the presser-foot 16 at substantially right
angles thereto and adapted to receive the sweat-band 22
upon its upper surface. Referring to Fig. 5, the end of
the base member 19 adjacent the presser-foot 16 is bent
back upon itself as at 23 in substantially U-shaped man- 30
ner, the upper and lower surfaces of this bent back por-
tion coinciding with the upper and lower surfaces of the
presser-foot 16 to provide a slot 24 extending from the
front edge 32 of the member 19 backward under the bent
back portion 23 and communicating with the under sur-
face of the presser-foot 16.

The bent back portion 23 is provided at the center 35
thereof with a threaded opening 25 receiving a screw 26.
A rectangular head-strap 27, substantially L-shaped in
longitudinal cross-section, is supported on the upper sur-
face of the bent back portion 23 at its flat end, having a 40
longitudinal slot 28 to receive the screw 26, and is sup-
ported at its downwardly bent end 29 upon the upper sur-
face of the base member 19 whereby to provide a chan-
nel 30 extending into the slot 24 and adapted to receive
the sweat-band 22.

It will be seen that loosening of the screw 26 permits 45
adjustment of the head-strap 27 and its downwardly bent
end 29 longitudinally along the upper surface of the bent
back portion 23 and the upper surface of the member
19, respectively, whereby to permit adjustment of the
channel 30 to accommodate sweat-bands of varying width.

The head-strap 27 is integrally formed with a down- 50
wardly projecting finger 31 adapted to engage the front
edge 32 of the base member 19 whereby to prevent angu-
lar displacement of the head-strap 27 about the screw 26.

The form of the invention shown in Figs. 3, 4 and 7 55
is identical with that shown in Figs. 1, 2, 5, 6 and 8, ex-
cept that the base member 19, the bent back portion 23
thereof and the head-strap 27 extend from the presser-
foot 16 in the opposite direction whereby to adapt the
device to right-hand feeding, whereas the form shown in 60
Figs. 1, 2, 5, 6 and 8 is adapted to left-hand feeding, and
like reference numerals identify like parts in each of the
several views.

Referring now particularly to Figs. 9—12, the sweat- 65
band 22 used for headwear is fed into the channel 30
from a spool 33 rotatively supported above the latter on
a stand 34.

The stand 34 consists of an L-shaped tubular bar 35 70
secured at its lower end to the sewing machine table
36 by means of a bracket 37 receiving the bar 35 in a
bearing 38, the bracket 37 being rigidly secured to the
sewing machine table by screws 39. The upper end of
the tubular bar 35 is horizontally bent and fixedly receives
a shaft 40, bent at substantially right angles to the 75
tubular bar 35, as shown in Fig. 11, and on which is
fixedly mounted the bearing bracket 41 by means of a
set-screw 42. A stationary disc 43, forming one side
of the spool 33 is rigidly secured to the flange 45 of
the bracket bearing 41 by means of screws 44 and abuts
one edge of a rotatable, cylindrical sleeve 46 contain- 80
ing the sweat-band 22 rolled thereon. The other edge
of the sleeve 46 abuts the movable disc 47, forming the
other side of the spool 33, and which is spring urged
against the rotatable sleeve 46 by a helical spring 48

sleeving the shaft 40, the outer end of the spring 48 abutting a fixed bearing 49, longitudinally adjustable along the shaft 40 by means of a set-screw 50.

A bearing 51 is rigidly secured to the side of the bearing bracket 41 by solder or the like and serves to fixedly support a shaft 52 in vertically adjustable positions by means of a set-screw 53.

The lower end of the shaft 52 is inwardly bent in a substantially horizontal direction as at 54. A bearing 55 is rigidly mounted on the inwardly bent portion 54 in horizontally adjustable positions by means of a set-screw 56 and has rigidly secured thereto at one side thereof a horizontally extending shaft 57. A bearing 58 is rigidly mounted adjacent the bearing 55 in horizontally adjustable positions by means of a set-screw 59 and is provided with an opening adapted to slidably receive the shaft 57, the sweat-band 22 passing downwardly between the shafts 57 and 54 intermediate the bearings 55 and 58 to be guided thereby into the cannel 30, as shown in Figs. 9, 10 and 12.

With the presser-foot or bracket 16 secured to the bottom of the presser-foot shaft 14 by means of the screw 18, as shown in Figs. 1 and 2, the sweat-band 22 is fed from the sleeve 46 through the shafts 54 and 57 and into the channel 30, passing under the presser-foot 16 intermediate the slot 20, the needle 21 and the bottom feed-dog 15, to be drawn therethrough in the usual manner during operation of the sewing machine. The head-strap 27 is adjusted longitudinally of the base member by means of the screw 26 to accommodate sweat-bands of varying widths, the bearings 55 and 58 being likewise adjusted along the shaft 54 for the same purpose.

By adjusting the longitudinal position of the bearing 49 along the shaft 40 by means of the set-screw 50, the tension of the spring 48 against the disc 47 is regulated, thereby regulating the frictional pressure between the disc 47 and the sleeve 46, thus regulating the length of sweat-band fed into the channel 30 during the stitching operation.

As shown in Fig. 1, a reversed hat 60 is suitably positioned with the lower edge of the crown below the needle 21 and slot 20 and underlying the sweat-band 22 and aligned with one edge thereof, in the usual manner of operation. With the hat 60 thus positioned, the slot 24 serves to properly guide the sweat-band 22 in line with the lower edge of the crown during the stitching operation, the portion 29 of the head-strap 27 serving to maintain the band 22 in proper position in the slot 24 within the channel 30.

Thus the head-strap 27 cooperating with the base member 19 provides an adjustable channel 30 which guides the sweat-band 22 in proper alignment above the lower edge of the crown of the hat 60 under the presser-foot or bracket 16 over the bottom feed-dog 15, the spool assembly 33 preventing overfeeding and wrinkling of the sweat-band while it is sewed to the hat.

It should now be apparent that there has been provided an adjustable headwear sweat-band feeder which may be readily and easily attached to a conventional sewing machine and which may be adjusted readily and easily to accommodate sweat-bands of varying widths while the sweat-band is being stitched in position on a headwear. It should also be apparent that there has been provided an adjustable sweat-band feeder adapted to cooperate with a spool assembly rotatively supported on a stand above the sewing machine for guiding the sweat-band used for headwear into proper position along the lower edge of the head-wear crown without overfeeding and wrinkling of the sweat-band while it is being stitched to the headwear, and which is adapted for either right or left-hand feeding.

While I have illustrated and described and preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a sewing machine for sewing sweat-bands to headwear and having a reciprocating needle, a presser-foot shaft and a bottom feed-dog, an adjustable sweat-band feeder comprising a horizontal presser-foot having an opening at one end adapted to receive the reciprocating needle, said presser-foot being upwardly and inwardly bent at the end remote from said opening whereby to form a hooked portion, means for securing said hooked portion to the bottom of the presser-foot shaft, a horizontal base member, said base member being upwardly and inwardly bent at one end whereby to form a second hooked portion, said hooked portion along one longitudinal edge being integrally formed to the end of said presser-foot adjacent said opening, the longitudinal axis of said base member extending outwardly from the longitudinal axis of said presser-foot at substantially right angles thereto and being adapted to receive a sweat-band across the top surface thereof, the transverse axis of said base member being upwardly inclined from the longitudinal axis of said presser-foot, a substantially L-shaped head-strap, said head-strap having a horizontal portion adapted to rest on the upper surface of said second hooked portion with the longitudinal axis of said horizontal portion aligned with the longitudinal axis of said base member, said head-strap having a vertical portion adapted along its lower edge to rest on said base member whereby to form a substantially rectangular channel intermediate said second hooked portion, said base member and said horizontal and vertical portions of said head-strap, means for longitudinally adjusting the position of said head-strap relative to said base member, said channel being adapted to receive a sweat-band therewithin extending under said presser-foot intermediate the reciprocating needle, said opening in said presser-foot, and the bottom feed-dog, and means for guiding and feeding the sweat-band into said channel.

2. For use with a sewing machine for sewing sweat-bands to headwear and having a reciprocating needle and a pressure foot shaft, a pressure foot member adapted to be secured at one end to the pressure foot shaft, said pressure foot member including a transversely extending base member at the other end thereof, a bent back U-shaped flange on the base member where it joins the pressure foot member and guide means adjustably secured to said flange in spaced parallel relation to said base member, whereby bands of various diameters may be guided therewith.

3. The combination of claim 2 wherein said guide means comprises a rectangular bar, an elongated slot in said bar and means extending through said slot and secured on said flange to permit sliding movement of the bar on the pressure foot member to accommodate varying widths of a sweatband.

4. The combination of claim 3 wherein said guide bar includes a bent end slidably retained on said base member and means on said bent end depending over a side edge of the base member to prevent angular displacement of said guide bar.

5. The combination of claim 4 wherein said last named means comprises a depending finger slidably engaging a side edge of the base member.
